UNITED STATES PATENT OFFICE

RICHARD RUHR, OF OFFENBACH-ON-THE-MAIN, AND HEINRICH LUDWIG HECKMANN, OF FRANKFORT-ON-THE-MAIN, GERMANY, ASSIGNEES TO THE FIRM OF MASCHINEN-FABRIK MOENUS AKTIENGESELLSCHAFT, OF FRANKFORT-ON-THE-MAIN, GERMANY

SOLE-LAYING MACHINE

Application filed December 3, 1928, Serial No. 323,507, and in Germany June 5, 1928.

This invention relates to sole laying presses and more particularly to such presses for cementing outsoles to lasted shoes. The invention is herein shown as applied to a revolvable frame carrying a plurality of pressing devices.

The principal object of the present invention is to provide improved means whereby the sole may be properly pressed to the sole 10 of the shoe and conformed thereto with the least effort of the operator and with the least loss of time.

In accordance with this object one feature of the invention contemplates the provision 15 of new means for supplying compressed air to the inflatable pads allowing the pads to remain in constant communication with the source of the compressed air as long as the pads are pressing on the sole. The pads remain inflated even if they leak.

Another feature of the invention consists 20 in new means for holding the shoe in working position so as to be easily gripped and released.

A further important feature of the invention consists in means for rotating several aligned revolvable frames by a common drive. Between the shafts of the frames means are 25 inserted adapted to couple any one of the frames with the common drive while uncoupling at the same time all other frames from the driving means.

Other features of the invention, including 30 certain details of construction and arrangements of parts will be hereinafter described and pointed out in the claims.

In the accompanying drawings,

Fig. 1 is an end-elevation of the machine,

Fig. 2 is a front-elevation of the machine 35 partly in section only single pressing devices being shown on the revolvable frames,

Fig. 3 is a longitudinal section of a part of the machine,

Fig. 4 shows on a greater scale a part of 40 the Fig. 1 with some parts in section,

Fig. 5 shows the means for locking and releasing the hold-down partly in section,

Fig. 6 illustrates in a plan-view the means 45 for coupling the revolvable frames to and uncoupling them from the common drive,

Figs. 7 to 9 show the air-controlling valve in three different positions and in a cross section along the line Y—Y of Fig. 10,

Fig. 10 is a vertical section along the line 55 X—X of Fig. 8,

Fig. 11 is a longitudinal vertical section of a cushion mould,

Fig. 12 is a plan view of the mould,

Fig. 13 is a plan view of the air-pad and

Fig. 14 is a longitudinal section of the same, 60

Fig. 15 is a plan view of the leather bag for the air pad and

Figs. 16 and 17 are a longitudinal and cross section of the bag respectively,

Fig. 18 is a longitudinal section of the 65 adapter,

Fig. 19 is a plan view, and

Fig. 20 a cross section of the adapter.

The sole-laying press consists of several 70 pressing devices every single pressing device being fastened to an arm 1 and every arm 1 being screwed by bolts 3 to a polygonal frame 2 revolvable in a standard 7.

As all single pressing devices are alike it 75 will suffice to describe one of them. To the arm 1 is fastened by screws 35 the disk-like mould 36 adapted to accomodate the air-cushion to be described. The fore-part 36' of the mould 36 can be adjusted by the screw 37 for different springs of the shoes. The part 36' is held by the bolt 38 and the spring 39 in contact with the fixed part of the mould 36 to form a continuous supporting surface for the air-cushion. The line 40 of contact 80 forms the pivot-axis for the movable part 36' as the bearing surface 41' of the lug 41 is cylindrical to the line 40.

The air-cushions consist generally of an 85 inflatable rubber-pad 42 covered by a leatherbag. The known rubber-pads consist on their hand of two substantially flat, oblong parts vulcanized at their margins to each other. But we prefer to provide a rubber

pad made of one integral piece to prevent 90 leakage. If the pad is to be made of two parts 42', 42'' we arrange the vulcanizing seam across the length of the pad as shown in Figs. 13, 14 because the length-seam as heretofore made is most liable to become defective. 95

The leather-bag consists likewise as a rule of two flat oblong parts connected together by a stitch or the like. The stitch is produced by sewing together the two outturned parts 5 of the bag. When the rubber-pad is inflated and the pressure is exerted on the shoe placed on the cushion the stitch has to withstand a very great tensile stress. It therefore happens often that this stitch as well as the material between the stitches is torn by the said stress. To avoid this inconvenience we give to the two parts 43, 44 of the leather-bag a box-like form, see Figs. 16, 17 and we sew the inturned overlapping edges by a double seam 10 45, 46. One end of the bag is open for the insertion of the pad and may be closed by a lace passed through the eyelets 47. A bag organized as just described has a greater strength, is easier to manufacture as the margins need not to be turned outward and is of 15 smaller size than the known bags. The leather-bag has a protective cover 48 the flaps 49 of which are sewn to the bag by the seams 45, 46 already mentioned.

20 To conform the cushion to the sole of the last to be worked upon an easily exchangeable adapter may be positioned upon or underneath the cover 48 of the bag. The adapter, see Figs. 18 to 20 consists of two layers 25 50, 51 of leather or of a textile fabric. Between these layers are incorporated the members 52, 53, and 54, of which the member 53 is the most important. It has two rolls 53', 53'' adapted to press the margins of the sole 30 33 against the curved instep of the shoe. The member 52 is flat; it is to be used for the tread-part of the sole and has several slits 52' allowing the member 52 to conform to this 35 part of the sole. The member 54 is to be used 40 for the heel part of the sole.

The adapter and the cushion are of the same outline and are accommodated as already stated in the mould 36. If the mould and the cushion are of dimensions suitable 45 for large-sized shoes and small shoes for instance children shoes are worked upon a boss 55 is likely to be produced in the cushion by the air-pressure as indicated in Fig. 11 and the rubber-pad is liable to burst at this point.

50 For different sizes of shoes it was hitherto necessary to fasten different moulds 36 by the bolts 3 to the arms 1. But we provide means allowing to use the same mould and cushions for different sizes of shoes. To this 55 end the mould 36 has a horse-shoe like part 36'' preferably extending over and above its heel-end. Under this part 36'' a rigid plate 56 may be inserted if small shoes are worked upon. This plate 56 is held down by the part 36'' as well as by the heel-part of the shoe itself.

With the cushion cooperates a hold-down 60 65 57 which engages with the foot 58 the heel part and with the foot 59 the fore-part of the shoe to hold it down while the cushion is

inflated by the compressed-air. The hold-down 57 is pivoted at 60 to the upper end of the two-armed lever 61 which swings about the pivot 62 of the arm 1. The lower arm of the lever 61 accommodates the spring 63 which abuts against a lug 64 fixed to the carrier 2. The spring 63 tends to lift the hold-down from the cushion and from the shoe. Adjacent to the lower arm of the lever 61 there is provided on the arm 1 a guide-way 65 for the toothed slide-block 66. This block 66 has an oblong hole 67 into which engages the bolt 68 on the rear-end of the hand-lever 69. The hand-lever 69 is pivoted at 70 in the arm 1, so that by manipulating the hand-lever 69 the block 66 may be moved on its guide-way 65 for locking or releasing the hold-down 57 inasmuch as the lower end of the lever 61 is provided with a tooth 71 for engaging the teeth of the block 66. A spring 72 attached at 73 to the arm 1 and at 74 to the block 66 tends to keep the latter in its highest position. By lowering the hold-down by hand toward the shoe the block 66 automatically rises and locks the hold-down 75 in its position. By swinging out the hand-lever 69 the block 66 is disengaged and the hold-down is released.

The rubber pad 42 has a nipple 75 connected by the hose 76 to the nipple 77 of the casing 78 of the air-controlling valve 79. The air is supplied by a compressor or any other suitable source and enters into the bore 80 of the casing 78 by the hose 20 attached to the nipple 81. It leaves the casing by the said nipple 77 and the hose 76 for the rubber-pad 42. The slide-valve 79 has three cup-leathers 82, 83, 84 and can be given by the handle 85 which is a prolongation of the shank 86 of the valve a threefold position 80 within the casing 78 thus affording to the air three different ways. In the position shown in Fig. 7 the compressed air passes through the annular chamber 87 between the cups 83, 84 and through the ports 88 into the nipple 77 leading to the air cushion. This position is retained so long as the shoe is in the working position on the cushion. Should the cushion leak fresh air is constantly supplied to the cushion so that the leakage does no harm and the shoe is not spoiled by having a not completely laid or cemented sole. After the sole is laid and glued the valve is given the position shown in Fig. 8 putting the ports 88 into communication with the exhaust-ports 89. By this means the air contained in the pad is allowed to escape whereupon the hold-down can be easily released and the shoe can be removed. In the case the air contained in the pad is to be cut-off from the air supply as well as from the exhaust ports the valve is given the position shown in Fig. 9.

The hose 20 mentioned above leads from a central duct of compressed air to be described below. The slide valve of every single 120

pressing device may communicate with the central duct by a hose 20. But we prefer to connect the slide valve of only one pressing device with the central duct and to supply the air to the valves of the other pressing devices by interconnecting the bores 80 of the casings of all valves. The interconnection is effected by providing in every valve-casing a cross-bore 90 and connecting the cross-bores 90 of the succeeding valves by hoses 91. It follows that only one valve casing has a bore 80.

Having thus described the organization of the single pressing device we wish to mention that while we have shown ten pressing devices arranged on the frame 2 their number may be varied at will. The frame 2 has a hub 4 fastened by screws 6 to a sleeve 5 journaled in the bearing 7 of the standard 7. The hub 4 abuts on one side of the bearing 7 and the ring 8 of the sleeve 5 abuts on the other side of the bearing.

The sleeve 5 forms on its hand a bearing for the short shaft 22. To the left hand end of the shaft 22 is fastened by the key 26 and the screw 27 the worm-wheel 25 engaged by the worm-shaft 25'. This shaft is driven by the pulley 92 whenever the treadle 93 is pressed down and it stops automatically after the frame 2 has been rotated for an angle contained between two successive arms 1. This step by step movement needs no further explanation as it is well known with sole laying machines of the kind described in the British Specification No. 7417/96. The wheel 25 has a circular path 28 into which engages the bracket 29 fastened to the standard 7 by the screw 30. By this means the shaft 22 is prevented from an axial displacement. On the right end of the shaft 22 is arranged a coupling member 24 free to slide thereon but rotatable therewith owing to the key 23. The member 24 has recesses 24' adapted to cooperate with the claws 21 of the sleeve 5. By means of the hand-lever 34 the claws 21 can be brought into engagement with the recesses 24' of the member 24 whereupon the frame 2 with the arms 1 is rotated in a step by step movement by the worm gear.

The wall of the sleeve 5 has a longitudinal bore 15 closed at the right end by the plug 17, see Fig. 3. The same end of the bore 15 is connected by the radial opening 18, the nipple 19, and the hose 20 to the casing 78 of the valve 79 of one of the pressing devices of the machine already described. The left end of the bore 15 communicates by the radial opening 16 with the annular chamber 14 of the casing 10. The casing 10 is held against rotation by engaging into the recess 7" of the bearing 7. The annular chamber 14 is on its hand in constant communication with the source of the compressed air by the nipple 13 so that compressed air is constantly supplied through the opening 16, the bore 15

and the opening 18 to the rubber-pads of the pressing devices. The contacting surfaces of the casing 10 and of the sleeve 5 are conical. Screw-nuts 11 are provided to assure a tight contact.

The machine so far described may be used as an independent, self-contained sole laying machine. But we have devised means allowing several such machines to be rotated one at a time by the same drive. To this end we place the several machines in alignment.

The first machine is organized as described. The additional machines are of the same construction with the exception that the left ends of their short shafts which are

denominated in this case by the numeral 31 carry instead of the worm-gear 25 a coupling member 32 fastened to it by a pin 33 and adapted to become engaged by the coupling-member 24 of the preceding machine.

The right end of every shaft 31 carries like the shaft 22 a coupling member 24.

It is to be easily understood that to operate the first machine the first coupling member 24 must be in engagement with the claws 21

of the sleeve 5 of the first machine. To operate the second machine the first coupling-member 24 is brought into engagement with the coupling member 32 of the second machine and the second-member 24 is brought

into engagement with the claws 21 of the second machine. To operate the last machine of the line all members 24 are in engagement with the respective members 32 except the last member 24 which is in engagement with the coupling claws 21 of the last machine.

At any time one machine only can be rotated.

Assuming the whole aggregate is at rest and all coupling-members 24 are in a middle position and engage neither the claws 21 nor the members 32. Now for instance the first machine from the left is to operate. By

pressing down the treadle 93 the shaft 22 is brought into a step by step movement. By

manipulating the first handle 34 the first member 24 is put into engagement with the claws 21 of the first machine. To the first

frame 2 is thus imparted a step by step rotation. All air-pads are empty and the valves

79 assume the position shown in Fig. 8. The attendant places the shoe and the sole which

have been provided with an adhesive and are to be cemented together into the pressing de-

vice just before him and lowers the hold-

down 57 which is automatically locked in its

position by the toothed block 66. He then

brings the valve 79 into position shown in

Fig. 7. The entering air inflates the pad and

conforms and presses the sole to the shoe. In

the meantime the next pressing device the

70

115

120

125

130

coupled. This is done by swinging the first hand-lever 34 in a clockwise direction and the second hand-lever 34 in an anti-clockwise direction. The first lever 34 brings the coupling-members 24 and 32 into engagement. At the same time this lever comes beneath the dog 35 of the first machine and locks it against rotation. The second lever 34 brings the next following coupling members 21 and 24 into engagement. The shafts 22 and 31 are therefore positively connected to each other so that the second machine begins to rotate. The second machine is now attended to in the same manner as the first machine. For operating of the third machine the second hand lever 34 is swung in a clockwise and the third hand lever 34 in an anti-clockwise direction. The following machines are operated in an analogous manner. The attendant remains on his place before every machine until all its pressing devices are supplied with shoes whereupon he proceeds to the next machine. After all machines have been supplied with shoes the attendant returns to the first machine. The shoes pressed in the first machine have in the meantime set, the adhesive has become dry, and fresh shoes may be introduced. To this end the first coupling member 24 is again moved in an anticlockwise direction. By so doing the first machine is coupled to the drive while all other machines are stationary. The shoes with the laid soles are removed from the first machine and fresh shoes are placed into the pressing devices of this machine. The further procedure is now self-explanatory.

We claim:

1. In a sole laying press, a stationary carrier, a frame revoluble on the carrier, a plurality of air pads on the frame, an air duct on the stationary carrier, an air duct interconnecting the air pads on the revoluble frame, a single air duct rotating with the frame and affording communication between the duct on the stationary carrier and the interconnecting duct on the revoluble frame, and a valve associated with every pad operated by a single lever for opening and closing the passage of the air from the interconnecting duct into the pad.
2. In a sole laying press, a stationary carrier, a frame revoluble on the carrier, a plurality of air pads on the frame, an air duct on the stationary carrier, an air duct interconnecting the air pads on the revoluble frame, a single air duct rotating with the frame and affording communication between the duct on the stationary carrier and the interconnecting duct on the revoluble frame, and a valve associated with every pad operated by a single lever for opening and closing the passage of the air from the interconnecting duct into the pad and for controlling the exhaust of the air from the pad.

3. In a sole laying press, an air pad, a box-like, two-part leather cover for the pad, and a protective layer on the cover with overhanging flaps, the margins of the parts of the cover and the flaps of the said protective layer being sewn together by the same seams. 70

4. In a sole laying press, an air pad, a mould accommodating the air pad, a horse-shoe-like border on and over an end of the mould, and a plate to be inserted underneath this border and preventing an excessive inflation of the pad at that end. 75

5. In a sole laying press, an air pad for pressing the sole to the lasted shoe, a hold-down for the shoe, a swinging two armed lever carrying at one end the hold-down, a sliding locking member at the other end of the said lever, a spring tending to bring this member in locking position, a handle for disengaging the locking member, and a spring for carrying the two-armed lever and the hold-down away from the shoe. 80

6. In a sole laying press, a plurality of aligned revoluble frames, a plurality of air-pads on every frame, a common motor-drive 90 for all frames, and means for coupling these frames one at a time to the common motor-drive.

7. In a sole laying press, a plurality of aligned revoluble frames, a plurality of air-pads on every frame, a common motor-drive 95 for all frames, a bushing on every frame journalled in a stationary bearing, a shaft within every bushing, and means for alternatively coupling the shaft with the bushing 100 thereon or with the following shaft.

8. In a sole laying press, a plurality of aligned revoluble frames, a plurality of air-pads on every frame, a common motor-drive 105 for all frames, means for coupling one of the frames to the common motor-drive, and means for preventing the rotation of the other frames.

9. In a sole laying press, an air pad, and a leather cover for the pad consisting of two parts sewn together at their margins, the latter being flanged toward each other and overlapped to form a box-like enclosure, and having a seam on the overlapped bent margins. 110

In testimony whereof we affix our signatures. 115
